UNITED STATES PATENT OFFICE.

DABNEY H. MAURY, OF EVANSTON, ILLINOIS.

WELL.

1,425,888.

Specification of Letters Patent. Patented Aug. 15, 1922.

Application filed October 22, 1921. Serial No. 509,539.

To all whom it may concern:

Be it known that I, DABNEY H. MAURY, a citizen of the United States, and a resident of Evanston, in the county of Cook and 5 State of Illinois, have invented certain new and useful Improvements in Wells, of which the following is a specification.

This invention relates to incased wells of the general type comprising an inlet terminal and a superposed casing separated by a water-tight bulkhead, said well casing forming a dry well pit and being of sufficiently large diameter to permit the installation on 10 the floor thereof, formed by said bulkhead, of pumping units large enough to be of an efficient type, and so located as to be at all 15 times accessible in place for purposes of inspection and repair.

Wells of the type specified are commonly 20 sunk by means of clam-shell or orange-peel buckets.

A principal object of the invention is to provide a well of the general type specified, the inlet terminal of which may be sunk and 25 the bulkhead separating the inlet terminal and well pit installed, without removing or expelling the water from the well casing.

As it relates to an inlet terminal which may be sunk without pumping or otherwise 30 removing or expelling the water from the well casing, I attain the object of the invention by means of a new and novel form of inlet terminal which I have devised, which may be built complete before being sunk, 35 and sunk as a finished unit ready for use.

As it relates to the installation of the bulkhead without removing the water from the well casing, I attain the object of the invention by a novel bulkhead construction, 40 comprising beams which extend across the well casing at the upper end of the inlet terminal, the ends of said beams resting upon seats formed in the inner sides of said well casing, and secured to the under side of said 45 beams are plank, or the like, which close the upper end of the inlet terminal and also form a platform on which the bed of concrete which forms the bulkhead proper is deposited, whereby said beams will become 50 embedded in the concrete forming said bulkhead and will impart necessary strength thereto to carry the weight of the pumps and other parts supported thereby.

The platform formed by the plank secured 55 to said beams also provides convenient support for setting the suction pipe or pipes for

the pump or pumps, which extend through said bulkhead into the inlet terminal.

In accordance with my invention, that portion of the bulkhead consisting of the 60 beams, the plank forming the platform and the suction pipe or pipes secured in proper position to said platform will be finished complete in advance and sunk to position in the well casing after sinking of the well cas- 65 ing has been completed.

An inlet terminal adapted for the practice of my present invention also comprises the various features and details of construction 70 hereinafter described and claimed.

In the accompanying drawings, in which my invention is fully illustrated,

Figure 1 is a vertical, sectional view on the line 1—1 of Fig. 2, of the inlet terminal and a portion of the superposed well casing 75 of a well embodying my invention.

Figure 2 is a sectional top plan view of the well, the section being substantially on the line 2—2 of Fig. 1.

Figure 3 is an enlarged, skeleton section 80 on the line 3—3 of Fig. 4, all concrete portions thereof and the filtering material being removed.

Figure 4 is a horizontal section on the line 4—4 of Fig. 3; and 85

Figure 5 is a top plan view of the finished well showing pumps installed.

For purposes of definite and concrete illustration, I have, in the drawings, shown my invention and improvements as embodied 90 in a well the well casing of which, including the supports for the inlet terminal, are made of concrete. The form of well shown is, however, merely typical, exemplifying a preferred embodiment of my invention, and I 95 do not, therefore, desire to limit my invention to use in wells of the particular construction shown, as persons familiar with well construction can readily adapt it for use in other forms of wells, as, for example, 100 wells the casings and inlet terminals of which are made of metal plates.

Referring now to the drawings, A designates the well casing, as a whole, B the inlet terminal as a whole, and C the bulkhead 105 which separates said inlet terminal from the interior of the well casing, as a whole, said well casing and bulkhead being water-tight, thus preventing access of water to the interior of the well casing, which, when 110 pumped out, will form a dry pump pit, of which said bulkhead forms the floor, said

well casing being of such large diameter that a pumping unit or units, indicated at D, may be installed on the floor thereof and will be accessible for purposes of inspection and repairs without removing the same from said well casing.

A further advantage of a well embodying my invention is that the pumping units can be located below the normal ground water level, thus eliminating the necessity for priming said pumps, as well as overcoming other difficulties incident to operating pumps under suction lift.

Also, owing to the large diameter of the well casing and inlet terminal, the well may be sunk by means of a clam-shell or orange-peel bucket.

To effect the object of the invention as it relates to a novel form of inlet terminal which may be built complete before being sunk, and sunk as a finished unit ready for use, said inlet terminal C comprises upright concrete supports 1 which extend from the bottom to the top of the inlet terminal and are shaped to define openings 2 in the sides of said inlet terminal through which water may flow into the same. At the outer side of the inlet terminal, the openings 2 are desirably of such large area that the inflow of water through the stratum adjacent to the outer side of the inlet terminal will be of such low velocity that practically none of the finer particles of sand in said stratum will be drawn into the inlet terminal by said inflowing current of water. The area of the openings at the inner side of the inlet terminal can be made relatively much smaller than the area of said openings at the outer side of the inlet terminal without causing appreciable friction losses, and this will enable the concrete supports 1 of the inlet terminal to be made sufficiently large to render said supports strong enough to sustain the stress to which they will be subjected in sinking the well, without breaking.

As shown, the sides of said supports 1 converge inwardly at substantially uniform angles.

Secured to the inner and outer sides, respectively, of the openings 2, are strainer plates 3 and 4.

The strainer plates 3 secured in the inner sides of said openings, are preferably made of thick durable metal, a desirable thickness in practice being about one-half an inch. The portions of said plates exposed between the upright supports 1 are perforated, a desirable size of perforations in most cases being about an inch in diameter.

In like manner, the portions of the strainer plates 4 exposed between the upright supports 1 are also perforated, a desirable size for said perforations, in most cases, being about two inches in diameter.

As shown, also, the outer strainer plates 4

extend entirely around the circumference of the inlet terminal, forming a sheet metal jacket therefor. In accordance with usual practice, said strainer plates comprise separate sections bent to the radius of the outer surface of the inlet terminal, the edges of which are connected by butt straps which overlap and are secured to the inner edges of adjacent plates, so that the outer surface of the jacket formed thereby will present a continuous, smooth and unobstructive surface, thereby facilitating sinking of said inlet terminal.

The bottoms of the openings 2 in the inlet terminal are closed by a concrete ring 5 formed integral with the upright supports 1 of said inlet terminal, the bottom side of said ring being outwardly and downwardly bevelled, terminating a short distance above the lower edge of the jacket formed by the outer strainer plates 4, which will thus form a sharp cutting edge suitable for sinking the inlet terminal and well casing.

As shown, the lower edge of said jacket is reinforced and strengthened by an angle iron secured thereto, which forms part of a flanged support 6 on which the lower edge of the concrete bottom ring 5 rests and which will secure the concrete portions and the outer jacket of said inlet terminal together during the process of sinking.

The upright supports 1 and the bottom ring 5 of the inlet terminal are, respectively, reinforced and strengthened by reinforcing bars 7 and 8 in a familiar manner.

With the described construction it is obvious that the openings 2 in the sides of the inlet terminal will form pockets, the lateral sides of which are closed by the upright concrete supports 1, the inner and outer sides by the strainer plates 3 and 4 and the bottoms thereof by the concrete bottom ring 5.

The inlet terminal having been otherwise finished, the pockets formed by the openings 2 are filled with filtering material 9, consisting of gravel, crushed stone, or the like, which is graded from relatively coarse material adjacent to the inner strainer plates 3 to relatively fine material adjacent to the outer strainer plates 4. To prevent loss of the relatively fine filtering material which rests in contact with the outer strainer plates 4, through the perforations therein during the process of sinking, the inner surfaces of said strainer plates are lined with thin material 10 provided with small openings, preferably usual wire fly screen, which is of such small mesh that the filtering material cannot pass through the same.

A simple and economical manner of constructing the inlet terminal B is as follows:—The strainer plates 4 are first connected to form the jacket for the outer surface of said inlet terminal and the per-

forated lining 10 secured to the inner side thereof. The flanged support 6 for the bottom ring 5 is then secured in position and thin metal plates 11, which form the lateral 5 sides of the molds for the upright concrete supports 1 are secured to the inner side of the jacket formed by the strainer plates 4 in proper position and the outer edges of said plates 11 connected in pairs to opposite 10 edges of the inner strainer plates 3, which, being relatively thick and strong, will form a rigid support for said plates 11.

The inner sides, not shown, of the molds for forming the upright supports 1 and the 15 bottom ring 5 are made of wood removably and temporarily secured in position, convenient means for securing the inner mold plates for the upright supports consisting in bolting the edges thereof to the inner 20 strainer plates 3, while the removable inner wall for the bottom ring 5 may be bolted to tie bars 12 the ends of which are connected to the lower edges of the inner strainer plates 3 and to the flanged support 25 6 for said bottom ring 5.

Also, to prevent bulging of the mold plates 11 under the weight of the concrete poured into the molds to form said upright supports, said plates are connected at intervals between their ends by tie bars 13. As shown, the plates 11 at opposite sides of each mold are thus connected by two tie bars spaced vertically.

After the inlet terminal has been finished 35 and the pockets formed by the openings 2 therein have been filled with filtering material, the upper ends of said pockets are closed by suitable coverings, indicated at 14, preferably made of wood and which rest 40 upon the bridge the spaces between the upper ends of the upright supports 1 of said inlet terminal and form supports on which the concrete for forming the superposed well casing A is deposited.

45 As the well is sunk, the superposed well casing A is extended upwardly, the mold therefor preferably consisting of a sheet metal outer shell 15 and a removable inner form, not shown, preferably made of wood 50 or other suitable material. The outer shell 15 of said mold is preferably built up from metal plates and is designed to form a permanent jacket for the well casing A, thus providing a smooth outer surface for said 55 well casing which will facilitate sinking of the well. Said metal jacket also tends to insure the watertightness of the well casing.

Directly above the inlet terminal, the well casing A is provided, on its inner surface, 60 with a seat for the bulkhead C, said seat being preferably formed by recessing the inner surface of the well casing A, as shown at 16, said recess forming shoulders 17 and 18 between which the edges of said bulk- 65 head will be confined.

The inlet terminal B and the superposed well casing A having been finished, the bulkhead C is next installed, the construction and the manner of installing the same being as follows:—

Said bulkhead comprises beams 19, which extend across the well casing and the ends of which rest upon the seat formed in the inner surface of the well casing by the shoulder 18 at the lower side of the recess 16 and secured to the under side of said beams are plank 20, which close the top of the inlet terminal and also form a support on which the concrete for the body portion 21 of said bulkhead is deposited.

In practice, the portion of said bulkhead C consisting of the beams 19 and platform 20 will be built and fitted to the upper end of the inlet terminal as soon as the shoulder 18 at the lower side of the recess 16 is formed, said platform being then removed and the erection of the well casing A continued.

As desired attachments to the bulkhead C, a suction pipe or pipes 22 for the pump or pumps D, a test pipe 23 and, if desired, a manhole 24 adapted to provide access to the inlet terminal C, may conveniently be set in proper position by securing them to the platform 20 after said platform has been finished.

The well casing having been finished and sunk to the full depth contemplated, the platform 20 with any attachments thereto, is lowered to position, with the ends of the beams 19 resting upon the seat formed by the shoulder 18, the edges of said platform 20 being preferably bevelled, as shown at 25, to facilitate engaging said platform with the open upper end of the inlet terminal. 105 Also, to close any space which may exist between the edges of said platform and the wall of the inlet terminal, batten plates 26 are secured to the top of the platform 20 which project outwardly and rest upon the shoulder 18.

The platform 20 having been set, the concrete portion 21 of the bulkhead is laid thereon, great care being exercised in depositing said concrete in order that segregation of the constituents of the concrete shall not occur.

The concrete portion of said bulkhead having been laid, a top dressing of neat cement grout is preferably applied thereto 120 under a head of water in the well casing to subject said cement grout to sufficient pressure to force it into the voids of the concrete, thus rendering said bulkhead absolutely water-tight.

The beams 19 are preferably I-beams and when the concrete portion of the bulkhead C is laid, it is obvious that they will be embedded therein, thus greatly reinforcing and strengthening said bulkhead.

After the concrete portion of the bulkhead C has hardened sufficiently the water is pumped out of the well casing, which will then form a dry pit on the floor of which 5 —formed by said bulkhead—the pump or pumps D may be installed and connection made to the suction pipe or pipes 22. With the described construction, it is obvious that said pumps and associated parts and apparatus will be readily accessible for all purposes.

I claim:

1. In a well of the type specified, the combination of an inlet terminal, and a superposed well casing, said inlet terminal comprising strainer plates, means for supporting said strainer plates in spaced relation, means for closing the bottom of the space between said strainer plates, and filtering material 20 contained in said space, said inlet terminal forming a structure which may be built complete before sinking and sunk as a complete unit ready for use, substantially as described.

25 2. A well as specified in claim 1, in which the outer strainer plate forms a jacket for said inlet terminal, substantially, as described.

3. A well as specified in claim 2, in which 30 the lower edge of the jacket formed by the outer strainer plate forms a cutting edge suitable for sinking, substantially as described.

4. A well as specified in claim 1, in which 35 a lining of thin material provided with small holes is applied to the inner surface of the outer strainer plate so that the filtering material may not escape outwardly through the perforations therein during sinking, 40 substantially as described.

5. A well as specified in claim 1, in which the outer strainer plate is of such large area 45 that the velocity of the water flowing into said inlet terminal will be too low to entrain with it an appreciable quantity of fine material from the surrounding water bearing stratum, substantially as described.

6. A well as specified in claim 1, in which 50 the inlet terminal comprises upright concrete supports which are spaced apart circumferentially of said inlet terminal and define openings through the sides thereof, in the inner and outer sides of which, respectively, the inner and outer strainer plates are secured, substantially as described.

55 7. A well as specified in claim 6, in which a concrete ring formed integral with the upright supports of said inlet terminal closes the bottoms of the spaces defined by said upright supports and strainer plates, substantially as described.

8. A well as specified in claim 6, in which 60 the lateral sides of the upright supports con-

verge outwardly, thus providing for making the outer sides of the openings defined by said upright supports of desired large area and said upright supports sufficiently large at their inner sides to impart adequate strength thereto, substantially as described.

9. In a well of the type specified, the combination of an inlet terminal, a superposed well casing, and a concrete water-tight bulkhead which forms a floor for said well casing above said inlet terminal and below the unpumped water 75 level, said well casing being sufficiently large to permit an efficient pumping unit of large capacity to be installed on the floor thereof and to render said pumping unit accessible without removing it from the well 80 casing, said bulkhead being so constructed and arranged that it may be installed below the unpumped water level without removing the water from the well casing, and a suction pipe secured in and which extends through 85 said bulkhead, substantially as described.

10. A well as specified in claim 9, in which the bulkhead in said well casing comprises a platform section consisting of planks secured to the under sides of beams the ends 90 of which are adapted to rest on a seat formed around the inside of the well casing, said platform section forming a closure for the upper end of said inlet terminal and a support on which the concrete section of said 95 bulkhead is deposited said platform section of the bulkhead being constructed in advance and sunk to place and the concrete portion of the bulkhead deposited thereon without removing the water from the well 100 casing, and a suction pipe secured to and which extends through said bulkhead, said suction pipe being set by securing it to the platform section of said bulkhead in proper position and sunk to place therewith, substantially as described.

11. A well casing as specified in claim 10, in which batten plates are secured to the platform section of the bulkhead and extend outwardly therefrom over and rest upon the 110 bulkhead seat formed in the inner side of the well casing, substantially as described.

12. A well as specified in claim 9, in which said inlet terminal comprises strainer plates, means for supporting said strainer plates in 115 spaced relation, means for closing the bottom of the space between said strainer plates, and filtering material contained in said space, whereby said inlet terminal may be built complete before sinking and sunk 120 as a finished unit ready for use, substantially as described.

In testimony that I claim the foregoing as my invention, I have hereunto affixed my signature this 30th day of September, 1921.

DABNEY H. MAURY.
